UNITED STATES PATENT OFFICE.

ALEXANDER RAE, OF MCKEESPORT, PENNSYLVANIA, ASSIGNOR TO JOHN F. RAE, OF MCKEESPORT, PENNSYLVANIA.

BRUSH-HOLDER.

No. 917,964.

Specification of Letters Patent.

Patented April 13, 1909.

Application filed October 12, 1908. Serial No. 457,300.

To all whom it may concern:

Be it known that I, ALEXANDER RAE, a resident of McKeesport, in the county of Allegheny and State of Pennsylvania, have invented a new and useful Improvement in Brush-Holders; and I do declare the following to be a full, clear, and exact description thereof.

My invention relates to brush holders for 10 dynamos or similar electric machines.

One object of the invention is to provide an improved form of connection between the supporting base for the holder and the head which holds the brush to provide for 15 both carrying such head and forming a proper electrical connection between the base and head.

A further object is to provide means for varying the pressure between the brush and 20 the commutator of the dynamo.

To these ends the invention consists, generally stated, in a brush holder comprising a base, and a head, and links connecting the base and head, and means for maintaining 25 the links in a proper electrical contact with the base and head.

It also consists in adjustable means for regulating the spring pressure between the base and head and thereby varying the 30 pressure between the brush and the commutator of the dynamo.

In the accompanying drawings Figure 1 is an end elevation of a dynamo showing the improved form of brush holder attached 35 thereto; Fig. 2 is a side elevation of the same; Fig. 3 is an enlarged plan view of one brush holder detached from the machine; Fig. 4 is a side elevation of the same; Fig. 5 is a vertical section on the line 5—5 Fig. 3; 40 and Fig. 6 is a detail sectional view.

In said drawings the base 1 is secured in any suitable way to a rod or holder 2 connected to the frame, being shown as having a clamping ring 3 slipping over the rod and 45 clamping thereon. The base 1 is provided with ears 4 which form supports for the shafts 6 which may be secured in position by set screws 7. The brush holder 10 is also provided with ears or lugs 11 in which are 50 secured shafts 12 by means of set screws 13, the construction in this regard being similar to the base 1. Extending between the base 1 and the brush holder 10 are the links 14 which are pivotally and slidably mounted 55 upon the shafts 6 and 12, having suitable bosses 15 and 16 at their respective ends. There are four of such links two on each side so that the base and brush holding head are capable of movement and are always held on lines parallel with each other, these 60 four connecting links forming the sole support for the head, including the current transmitting means between the head and base. Around the shafts 6 and 12 and between the bosses of the links as shown are 65 the coiled tension springs 17 whose function is to maintain the links in close electrical contact with the lugs 4 and 11 on the base and head. The head is therefore free to swing upon the base under any suitable 70 spring pressure so as to hold the brush mounted in the head against the commutator while proper electrical contact is always maintained between the head and base through the links 14.

The head can be of any suitable construction for supporting the brushes. I have shown it as having a hollow rectangular seat in which is mounted the plate 18 controlled by adjusting screws 19 for clamping 75 the brushes firmly in the holder. While any suitable spring device to hold the head under pressure and so hold the brushes against the commutator may be employed I have provided a simple and strong device for this 80 purpose which gives a compact construction to the brush holder, being located within the frame and between the connecting links. For this purpose I employ the yoke 19 supported on the stem 20 formed with or connected rigidly to the base 1, said yoke being 85 located within and between the links 14, said yoke supporting a shaft 21 around which is coiled the tension spring 22, one end of which passes up between the springs 90 17 fitting around the shafts 12 mounted in the ears 11 of the head 10 and carries at its upper end a knob or button 23 pressing upon one of said springs and thereby exerting pressure to hold the brushes mounted 95 in the head in contact with the commutator. I prefer to mount the knob 23 loosely on the free end 24 of the spring so that it may adjust its position under the different pressures brought upon the spring. The other 100 end 25 of the spring 22 projects outwardly, forming the handle for the adjustment of the spring and engages with a ratchet 26 rigid on the one arm of the yoke 19, such ratchet having teeth adapted to hold the 110

free end 25 of the spring in place so that by the adjustment of the said arm 25 upon the ratchet the pressure of the spring 22 may be varied and in this way vary the pressure 5 of the brush upon the commutator, taking up any lost motion required for that purpose either from the wear of the brushes or relaxing of the spring, and thus regulating the tension of the brushes upon the commutator.

By the construction above set forth it will be noted that the connecting links 14 provide a durable mechanical and electrical connection between the base and the brush 15 holding head, serving both functions to support the head and form proper electrical connection between said base and head, doing away with the necessity of the employment of the usual series of copper or like 20 strips between the base and head, while on account of their use I am enabled to provide a more compact brush holder by placing the controlling spring within the same instead of outside thereof, and I am also enabled to 25 provide a simple means for varying and controlling the pressure of the brushes upon the commutator.

What I claim is:

1. A brush holder comprising a base, a 30 head, links connecting the base and head, and means for maintaining said links in proper electrical contact with the base and head.

2. A brush holder comprising a base and 35 head, links pivoted to the base and head and supporting the head and springs acting on said links for maintaining them in proper electrical contact with the base and head.

3. A brush holder comprising a base and 40 head, links pivotally and slidably mounted on said base and head, and means for maintaining said links in proper electrical contact with the base and head.

4. A brush holder comprising a base and 45 head, each having ears thereon, shafts secured in said ears, links pivotally and slidably mounted on said shafts and means for maintaining said links in electrical contact with the base and head.

5. A brush holder comprising a base and 50 head, each having ears thereon, shafts supported in said ears, links pivotally and slidably mounted on said shafts, and springs confined between said links and adapted to 55 hold them in proper electrical contact with said ears.

6. A brush holder comprising a base and

head, links connecting the base and head, springs acting on said links for maintaining them in proper electrical contact with the 60 base and head, and adjustable means mounted between said links for exerting pressure upon said head.

7. A brush holder comprising a base and head pivotally connected, a yoke supported 65 by the base and carrying a coiled tension spring having one arm operating upon the head and another free arm and means for holding and adjusting the pressure of said spring.

8. A brush holder comprising a brush and head pivotally connected, a yoke mounted on said base, a ratchet carried by said yoke, and a tension spring mounted in the yoke having one arm engaging with the head and 75 the other arm adapted to engage said ratchet.

9. A brush holder comprising a base and head, pivotally and slidably mounted links connecting said base and head, means for 80 maintaining said links in electrical contact with said base and head, a yoke secured to the base and mounted between said links and carrying a tension spring acting upon said head and means for adjusting the tension of said spring.

10. A brush holder comprising a base and head, pivotally and slidably mounted links connecting said base and head, means for maintaining said links in electrical contact 90 with the base and head, a yoke secured to the base between said links and having a ratchet and a coiled spring mounted in the yoke and having one end acting upon the head and the other end adapted to engage 95 with said ratchet.

11. A brush holder comprising a base and head, links connecting the base and head, means for maintaining said links in proper 100 electrical contact with said base and head, and means for exerting pressure on said head to force it against the commutator.

12. A brush holder comprising a base and head, links pivotally connected to said base and head, means for maintaining said links 105 in proper electrical contact with said base and head, and spring means attached to said base and exerting pressure on said head.

In testimony whereof, I the said ALEXANDER RAE have hereunto set my hand.

ALEXANDER RAE.
